ARTICLE-HANDLING DEVICE FOR RACKS

Francis M. Baluck, Oak Park, Anton J. Brunner, Congress Park, and Heinz F. Runge, Chicago, Ill., assignors to Western Electric Company, Incorporated, New York, N.Y., a corporation of New York

Application November 26, 1954, Serial No. 471,232

8 Claims. (Cl. 198—26)

This invention relates to conveyors, and more particularly to escapement devices for conveyors of racks carrying wire spring relay combs.

An object of the invention is to provide new and improved conveyors for wire spring relay combs.

Another object of the invention is to provide apparatus for automatically transferring racks of articles from chutes or slides to conveyors.

Another object of the invention is to provide a new and improved apparatus for feeding racks seriatim from slides to a trackway.

An article-handling device illustrating certain features of the invention may include a slide down which article-carriers may travel in tilted positions, escapement means for permitting the article-carriers to move off the slide one at a time to a transversely extending trackway. Means are provided to permit the article-carriers to swing to vertical positions at the discharge end of the slide, and swinging-damping means limit the swinging of the article-carriers.

An apparatus illustrating the invention more in detail may include a plurality of racks for holding and masking portions of wire spring relays and a grit blaster for blasting flash from the wire spring relay combs. A pair of rails are provided along which rollers on the racks rest to transport the racks through the grit blaster and an inclined ramp or slide having an indexing or escapement mechanism at the lower end thereof which is provided for supplying the racks one at a time to the guide rail. The escapement mechanism may include three pairs of stops spaced along the ramp so operable that when the intermediate pair of stops are in retracted positions the end pairs of stops block movement of the racks down the slide, and when the end pairs of stops are retracted, the intermediate pair of stops is in blocking position to let only one rack move off the slide at one time. The slide may be so constructed and arranged that the racks tilt as they slide down the slide, and means are provided at the lower end of the slide to permit the racks to swing to vertical positions and to damp swinging of the racks.

A complete understanding of the invention may be obtained from the following detailed description of a conveyor forming a specific embodiment thereof when read in conjunction with the appended drawings, in which:

Fig. 1 is a fragmentary, vertical section of a portion of a conveyor forming a specific embodiment of the invention;

Fig. 2 is a fragmentary vertical section taken along line 2—2 of Fig. 1;

Fig. 3 is a fragmentary, partially sectional, top plan view taken along line 3—3 of Fig. 1;

Fig. 4 is a fragmentary vertical section similar to Fig. 2;

Fig. 5 is a vertical section taken along line 5—5 in Fig. 3;

Fig. 6 is an enlarged fragmentary vertical section taken along line 6—6 of Fig. 1;

2

Fig. 7 is a vertical section taken along line 7—7 of Fig. 6;

Fig. 8 is an enlarged elevation of a portion of the apparatus shown in Fig. 1; and

Fig. 9 is a vertical section taken along line 9—9 of Fig. 8.

Referring now in detail to the drawings, there is shown therein a machine for grit blasting wire spring relay combs 10 (Fig. 8) to remove flash from wires 11 of the combs adjacent to plastic blocks 12 molded around the wires. The combs are placed on carrying fixtures or racks 21, each of which is provided with a carrying rod 22 fastened rigidly to the top of a frame 19, and pairs of rollers 23 and 24 are mounted on the frame below the rods 22. The combs 10 are clamped on the frame by an apertured door 26 mounted pivotally on a spring-mounted pin 27 and latched in position by a latch 28. The door 26 is provided with a groove 29 and the frame 19 with a groove 30 for receiving and masking a molded bar 32 of the comb 10 to protect the bar 32 during blasting. The door 26 also is provided with a groove 33 for masking dowel pins 34 secured to the block 12. When the door is not secured by the latch 28, the pin 27 urges it to an open position slightly greater than 90° from its closed position. The racks 21 are placed on guide rails 55 of a chute 56 (Figs. 1 and 3) supported by posts 61 extending upwardly from a plate 62 mounted on a column 63. As the racks 21 travel down the chute 56 they pass under upper guides 77 and come to escapement bars 78 of an escapement unit 79 (Figs. 2 and 6), drivable through racks 80 and 81 and pinions 82 fixed to a shaft 83. The shaft 83 is mounted rotatably in fixed supports 85 and 86, which also support rotatably a shaft 87 having pinions 88 keyed thereto and are connected by a plate 84. The shaft 87 is connected through gearing 89 in a fixed housing 90 to a shaft 91 having a lever 92 keyed thereto and supporting a roller 93 at its free end. The lever 92 normally is biased to the position thereof shown in Fig. 6 by a torsion spring 94 secured at its ends to the shaft 87 and to the support 86. However, when the lever 92 is swung in a clockwise direction, as viewed in Fig. 6, the shaft 87 turns the pinions 88 keyed thereto in a direction lifting stop bars 97 having gear rack portions 98 relative to the supports 85 and 86 and the chute 56. The pinions 88 also engage rack portions 95 of stop bars 99 to move the bars 99 downwardly into the path of the article-carrying racks 21 on the chute 56, and gear rack portions 100 on the bars 99 turn the pinions 82 to raise the stop bars 78 out of the paths of the rods 22 of the racks 21 on the chute 56 to let one of the racks 21 slide past the stop bars 78 to the stop bars 99.

As the rack 21 slides past the bars 78 (Fig. 2), a shoe 111 thereof clears rack-dragging or tilting rods 112 of the chute 56 and the rack 21 swings to a vertical position, brushing past spring-pressed swing-damping levers or bell cranks 113 as the rack 21 so swings. The levers 113 are mounted pivotally on pins 102 secured to frames 103 supporting the rods 112, and are urged in counterclockwise directions, as viewed in Fig. 2, by tension springs 105. Pins 106 limit counterclockwise movement of the levers 113, and end portions 107 of the levers 113 act as stops to limit swinging of the racks 21 in a clockwise direction. This rack 21 then hangs vertically. A resilient pad 114 composed of polytetrafluoroethylene is mounted on a vertical stop plate 115 supported by the plate 62 for taking the impact of the swing of the rack 21 as it comes off the rods 112.

The lever 92 is swung against the action of the spring 94, as described above, by a cam lug 116 carried by a grit blasting conveyor chain 117 (Fig. 1) coursing on

sprockets 118 and moved past the lever 92 as the lug 116 removes from the end of the chute 56 the rack 21 previously released by the bars 97 when they were lifted by the preceding lug 116. When the lug 116 clears the lever 92, the spring 94 returns the lever 92 and the bars 78, 97 and 99 to their former positions in which the bars 78 and 97 stop movement of the racks 21 down the chute 56, and the bars 99 are retracted to release the rack 21 held thereby, which slides on down to the bars 97. The motion of the bars 78 and 97 relative to the bars 99 is such that the bars 78 and 97 are in rack-blocking positions before the bars 99 are withdrawn from rack-blocking positions. The chain 117 has rollers 119 having peripheral ribs 120 which travel along grooves 12 in C-guides 124 and 125 supported by standards 126.

As each rack 21 is released by the bars 97, it slides down the chute 56 and drops off the end thereof onto supporting rollers 121 and onto a guide rail 122 over which the rollers 23 and 24 project. An end 123 of the guide rail 55 prevents the upper portion of the rack 21 from bouncing back to the right, as viewed in Fig. 5. Then, as the next lug 116 comes along to the chute 56, the lug engages the rod 22 of the rack 10 just released by the bars 97 and pushes the rack edgewise along the guide rails 122 and 128 (Figs. 2 and 3), the guide rail 128 having a camming portion 129 which centers the rack 21 between the guide rails 122 and 128 as the rack 121 is moved edgewise therebetween.

The lugs 116 push the racks 21 edgewise along the guide rails 122 and 128 through a grit blaster (not shown) of a well known type, in which grit is blown against the portions of the wires 11 adjacent to the molded blocks 12 and 32 (Fig. 10) to clean flash formed in molding the blocks from the wires. The door 26 and the body 19 of the rack 21 mask the blocks 12 and 32 from the grit while the flash is removed from the portions of the wires adjacent thereto.

The above-described apparatus serves to effectively feed the racks 21 from the chute 56 to the tracks 122 and 128 without possibility of jamming thereof, and feeds the racks surely. Certain features of the apparatus described above are disclosed and claimed in copending application Serial No. 471,201, filed November 26, 1954, by A. J. Brunner and J. R. Marcus for "Article-Handling Devices."

It is to be understood that the above-described arrangements are simply illustrative of the application of the principles of this invention. Numerous other arrangements may be readily devised by those skilled in the art which will embody the principles of the invention and fall within the spirit and scope thereof.

What is claimed is:

1. An article-handling device, which comprises a pair of inclined rails, a plurality of racks each of a predetermined height and having portions extending from opposite edges thereof for engaging the rails to suspend the rack from the rails and slide down the rails, means for tilting the racks as the racks slide on the rails, a movably mounted swing-damping bell crank supported in a normal position, one arm of said bell crank provided with a cam surface so as to be engaged and moved by each rack as the rack swings away from the tilting means, and means for biasing the bell crank to said normal position so as to prevent rebound of the aforementioned racks.

2. An article-handling device, which comprises a pair of inclined rails, a plurality of racks each of a predetermined height and having slide portions extending from opposite edges at the upper end of the rack for engaging the rails to suspend the rack from the rails and slide down the rails, an escapement positioned near the lower ends of the rails for permitting the racks to slide off the rails one at a time, means for tilting the racks as the racks slide down the rails to the escapement, said tilting means serving to release each rack to permit the rack to swing to a vertical position as the rack moves through

the escapement, a spring-pressed damping lever positioned so as to be moved by the rack as the rack swings away from the tilting means and prevent swinging of the rack back to the tilting means, a trackway for receiving the racks from the rails, and a resilient bumper positioned at the trackway for damping swinging of the racks.

3. An article-handling device, which comprises a pair of inclined rails, a plurality of racks each of a predetermined height and having portions extending from opposite edges at the upper end thereof for engaging the rails to suspend the rack from the rails and slide down the rails, a trackway positioned at the lower ends of the rails for receiving the racks therefrom, means for tilting the racks as the racks slide down the rails, said tilting means serving to release each rack as that rack approaches the trackway, and a movably mounted swing damping means positioned so as to be engaged and moved by a rack as the rack is released from the tilting means and prevent swinging of the rack back to the tilting means.

4. An article-handling device, which comprises a plurality of racks each of a predetermined height and having slide portions extending from opposite edges near the upper end thereof, a trackway, a pair of inclined rails sloping downwardly to the trackway for supporting the racks from the slide portions, means for retarding the lower ends of the racks relative to the upper ends thereof as the racks slide down the rails, said retarding means serving to release each rack as that rack moves to the lower ends of the rails, a spring-pressed arm positioned so as to be moved by a rack as the rack swings away from the retarding means to lessen swinging of the rack, and a resilient bumper positioned at the trackway for damping swinging of the racks.

5. An article-handling device, which comprises a plurality of racks each having pins projecting from the ends thereof, a pair of inclined guide rails down which the pins may slide, a first pair of stops, a second pair of stops, a third pair of stops, means for mounting the pairs of stops at the lower end of the guide rails movably between forward positions extending into the path of the racks and retracted positions out of the path of the racks and in positions in which the second pair of stops is positioned between the other pairs of stops, rack and pinion means for moving the pairs of stops so that the second pair of stops is in its retracted position when the other pairs of stops are in forward positions and the second pair of stops is in its forward position when the other pairs of stops are in their retracted positions, guide means spaced from the inclined guide rails for tilting the racks approaching the first pair of stops, said guide means terminating in the vicinity of the first pair of stops to permit swinging of the racks to a vertical position as the racks pass said first pair of stops, and means engaged by the swinging racks for retarding movement of the racks.

6. An article-handling device, which comprises a plurality of racks each having supports projecting from opposite edges thereof, a pair of inclined guide rails down which the supports may slide, escapement means mounted at the lower end of the guide rails movable between a rack-blocking position and a retracted position out of the path of the rack, guide means positioned below the guide rails for tilting each rack as it approaches the escapement means to prevent swinging of the racks as the rack engages the escapement means, said guide means terminating in the vicinity of the escapement to permit swinging of a rack passing through the escapement, and spring-biased levers positioned to engage and retard swinging of a rack passing through the escapement.

7. An article-handling device, which comprises a plurality of racks each having pins projecting from the ends thereof, a pair of inclined guide rails down which the pins may slide, a first pair of stops, a second pair of stops, a third pair of stops, means for mounting the pairs of stops at the lower end of the guide rails movably between forward positions extending into the path of the racks and

retracted positions out of the path of the racks and in positions in which the second pair of stops is positioned between the other pairs of stops, rack and pinion means for moving the pairs of stops so that the second pair of stops is in its retracted position when the other pairs of stops are in forward positions and the second pair of stops is in its forward position when the other pairs of stops are in their retracted positions, guide means positioned below the guide rails for tilting each rack as it approaches the first pair of stops to prevent swinging of the rack, said guide means permitting each rack to swing therefrom as the rack moves from the first pair of stops to the second pair of stops, a pair of levers urged into the path of each rack as the rack swings from the guide means to slow the swinging of the rack and to limit the return swing of the rack.

8. An article-handling device, which comprises a plurality of racks each having pins projecting from the ends thereof, a pair of inclined guide rails down which the pins may slide, a first pair of stops, a second pair of stops, a 20 third pair of stops, means for mounting the pairs of stops at the lower end of the guide rails movably between for-

ward positions extending into the path of the racks and retracted positions out of the path of the racks and in positions in which the second pair of stops is positioned between the other pairs of stops, rack and pinion means for 5 moving the pairs of stops so that the second pair of stops is in its retracted position when the other pairs of stops are in forward positions and the second pair of stops is in its forward position when the other pairs of stops are in their retracted positions, guide means positioned below the guide rails for tilting each rack as it approaches the stops to prevent swinging of the racks, and a latch for permitting each rack to swing therewith in one direction and preventing swinging movement of the rack thereback.
